CARTRIDGE MAGAZINE

Jacob Sofinowski III, Baldwin, and Robert W. Schnepfe, Jr., Upperco, Md., assignors to AAI Corporation, Cockeysville, Md.

Filed Dec. 3, 1975, Ser. No. 637,348

Term of patent 14 years

Int. Cl. D22—05

U.S. Cl. D22—7

FIG.1

FIG. 3

FIG. 4

FIG. 2

FIG. 5

FIG. 6

FIG. 1 is a perspective view of a cartridge magazine according to the invention, with the normally bottom end facing upwardly.

FIG. 2 is an inverted perspective view of the cartridge magazine of FIG. 1.

FIG. 3 is an elevation view looking toward the narrow front facing side of the cartridge magazine as shown in the view of FIG. 2.

FIG. 4 is an elevation view looking toward the right rear wide facing side of the cartridge magazine as shown in the view of FIG. 2.

FIG. 5 is an elevation view looking toward the left front facing wide side of the cartridge magazine as shown in the view of FIG. 2.

FIG. 6 is an elevation view looking toward the nar-

row rear facing side of the cartridge magazine as shown in the view of FIG. 2.

FIG. 7 is a top plan view of the cartridge magazine.

FIG. 8 is a bottom plan view of the cartridge magazine.

We claim:

The ornamental design for a cartridge magazine, substantially as shown.
